DUST-ELIMINATOR

Nicholas V. Goss, Weedsport, N. Y.

Application May 24, 1944, Serial No. 537,135

1 Claim. (Cl. 145—35)

1

The invention relates to a hand saw attachment, and more particularly to a dust-eliminator device for use on hand saws.

The primary object of the invention is the provision of a device of this character, wherein on the mounting thereof upon a hand saw through motion of the latter in the cutting of work the sawdust that accumulates at the kerfs made by the teeth of the saw in its operation will be blown away, the device being actuated solely by the motion of the saw when in use.

Another object of the invention is the provision of a device of this character, wherin the working of the piston which function as a blower medium will be silenced in its motion in a unique and novel manner, the piston being actuated through motion imparted to the hand saw.

A further object of the invention is the provision of a device of this character, where the same can be readily and easily detachably applied in position on the hand saw for the working of such device when handling the said saw for the cutting of work, the device being held within a spring clip attached to the handle end of the saw.

A still further object of the invention is the provision of a device of this character, which is simple in construction, thoroughly reliable and efficient in the operation thereof, readily and easily attached to a hand saw, strong, durable, self-operating, compact, and inexpensive to manufacture and install.

With these and other objects in view the invention consists in the features of construction, combination and arrangement of parts as will be hereinafter more fully described, illustrated in the accompany drawing, which shows the preferred form of the invention, and thereafter pointed out in the claims annexed hereto.

In the accompanying drawing:

Figure 1 is a fragmentary side elevation of a hand saw showing the device constructed in accordance with the invention applied thereto.

Figure 2 is a front end view of the device held within a mounting therefor.

Figure 3 is a sectional view taken on the line 3—3 of Figure 2 looking in the direction of the arrows.

Figure 4 is a view similar to Figure 3 looking toward the other or rear end of the device.

Figure 5 is a side view of the mounting clip for the device.

Figure 6 is a partial sectional view taken on the line 6—6 of Figure 2 looking in the direction of the arrows.

Figure 7 is a perspective view of the piston used in the device.

Similar reference characters indicate corresponding parts throughout the several views in the drawing.

Referring to the drawing in detail, A designates

2

generally a portion of the blade of a saw having an ordinary handle B, these being secured together in the usual way and the saw is of a common hand-operated type, while associated with this saw is the dust-eliminator device C constituting the present invention and herein-after set forth in detail.

The device C comprises a cylinder 10 of a determined length having opposite end heads 11 and 12, respectively, and within this cylinder 10 is a floating piston 13 which is adapted to reciprocate between the heads 11 and 12 under the hand operation of the saw. The cylinder 10 is of uniform cross-sectional size throughout its longitudinal extent, the length of such cylinder 10 being sufficient to allow of the proper extent of travel of the piston 13 therein for a blowing operation in a manner presently described.

The piston 13 at the center thereof longitudinally of the axis of the cylinder 10 has provided therein an opening 14 which extends through the opposite faces of the said piston, has compressed therein rubber strands 15 which seal such opening and protrude beyond the opposite faces of the same for a determined distance to provide bumper areas 16 to contact the inner walls of the end heads 11 and 12, respectively, to silence any pounding action of the piston 13 when the same is reciprocated within the cylinder 10 in the operation of the device, the resiliency of the strands 15 being effective for absorbing the impact of the piston on the said heads.

In the head 11 is provided an aperture 17 which in its disposition is arranged at one side of the teeth 18 of the blade A of the saw, yet close to the row of such teeth when the cylinder is attached to the said saw the piston 13 in the operation thereof will blow sawdust from the kerf cut by the saw in the use thereof for cutting of work. Additionally, this head 11 is provided with a channel 19 for the seating of the inner end edge of the blade A of the saw therein to properly set the device as to the opening 17 with relation thereto.

The other head 12 is provided with several apertures 20 which are adapted to expel air from the cylinder 10 when the piston 13 moves rearwardly therein when the latter is operating under motion imparted to the saw in the use thereof.

The heads 11 and 12 are removably fitted in the ends of the cylinder in any suitable manner for secure attachment thereto in the successful operation of the device.

Fitted to the lowermost edge of the handle B of the saw by fasteners 21 is the outstruck crown portion 22 of a cylinder clip or hanger mounting 23 having the two pairs of springy snap-engaging arms 24, which are located at opposite ends of the said clip or mounting for the firm

detachable fastening of the cylinders 10 therein with the inner end edge of the blade A seated in the seating channel 19 within the head 11 which is at the front end of the device when held upon the saw.

The arms 24 are provided with inturned holding ears 25 so as to avoid any displacement of the cylinder 10 within the clips as might occur in the use of the saw when cutting work.

When the device is worn on the saw and the latter is in use, the reciprocation of the same results in forcing the piston 13 back and forth. When this piston moves forward in the cylinder 10 a blowing action takes place through the aperture 17 in the head 11 directing air under pressure in the direction of the teeth 18 working in the kerf cut thereby in a piece of work so as to blow away the sawdust from such kerf, the device being automatically operated under the motion of the saw when manually handled for sawing purposes.

What is claimed is:

A dust eliminator device of the kind described, comprising a cylinder having front and rear inset end heads, a floating piston reciprocatively movable within the cylinder, a channel formed in the front end head to receive the rear edge of a saw blade, an aperture in said front end head on one side of said channel adjacent the lower end thereof, a plurality of relatively spaced aper-

tures in the rear end head of said cylinder, a central longitudinally axial opening provided in the piston, rubber strands compressed therein and protruding beyond the ends thereof to act as a noise silencer for the piston and for cushioning action thereof against the heads of the cylinder on reciprocation of the said piston therein, and means for mounting said cylinder, said means being attached to the lower surface of the saw handle, and said aperture being located to one side of the saw blade and substantially in alignment with the teeth of the saw so that air emitted from the aperture in said front end head will be blown directly over the cutting teeth of the saw blade.
